ELECTRIC CLOCK

Irving Florman, New York, N. Y.

Application June 24, 1931, Serial No. 546,615

8 Claims. (Cl. 58—26)

This invention relates to electric clocks and more particularly to clocks of the type having a non-self-starting motor.

Electric clocks are known having two types of motors. In the first type, the motor starts automatically whenever the current is turned on. In the second type, the turning on of the current is not enough to start the motor and it is necessary to give an impulse to the rotor member manually or in some other fashion in order to restart the clock. For various reasons, clocks of this second type have proven to be more satisfactory in actual use. For one thing, the fact that the clock has stopped is at once evident since it is no longer running, whereas a short break in the current with a self-starting clock may deceive the user since the clock will start to run again as soon as the current is restored. Devices for starting clocks of the non-self-starting type have been devised, but none of them have been particularly satisfactory as it is difficult to impart to the rotor sufficient speed by mere manual rotation of a knob or the like and as it is sometimes not realized that it is necessary to start the clock manually.

The primary object of the present invention is to provide means in an electric clock of the non-self-starting type such that whenever the clock is set the rotor will automatically be started. More specifically, it is the object of the invention to provide a clock of this type in which the clock must be raised in order for the hands to be set to the correct time after the motor has stopped, and in which the replacement of the clock on a support automatically starts the rotor. A further object of the invention is to provide an arrangement for starting a rotor in which energy, such as that of a spring, is stored up and is then suddenly released upon the rotor, so that great starting speed may be imparted to the rotor with a less degree of effort. Another object is to permit manual operation of such starting means.

A second object of the invention is to supply a clock having two spaced oppositely facing dials, so that the clock may be located for instance on the usual table between a pair of beds and may be seen by the occupant of either. It is a further object of the invention to provide such a clock in which the hands are driven in opposite directions from a single driving means. It is a further object of the invention to provide a setting means by which the hands of both dials may be set at the same time in opposite directions. A still further object of the invention is to provide a simple, strong and efficient construction to accomplish these results.

More specifically, my invention contemplates a clock having openings in the base, with a member extending through one of these openings which contacts with a support on which the clock is placed and which will be moved upward thereby. Connected to this member is means such as a pawl or lever arrangement so that spring energy may be stored up and suddenly released to act on the rotor. Through another opening in the base extends a setting stem, so that the clock must be raised in order to turn the hands to the proper time after the current has failed. In this way, after the hands are set, the mere replacement of the clock on the support will start the rotor and thereby drive the clock.

Further objects and advantages of the invention will be more apparent from the following description when taken in conjunction with the accompanying drawings which form a part thereof.

In the drawings:

Fig. 1 is a front elevation of a clock embodying my invention, with parts in section.

Fig. 2 is a side elevation.

Fig. 3 is a bottom plan view.

Fig. 4 is a front elevation of the clock with the dial removed.

Fig. 5 is a rear elevation of the clock with the dial removed.

Fig. 6 is a rear elevation of the clock with the dial and supporting plate removed.

Fig. 7 is a fragmentary cross section on the line 7—7 of Fig. 6.

The clock in general is provided with a base 2 of stone, marble or any suitable material. Secured to this base 2 by screws 4 is a metallic plate 6 carrying at either side upstanding supporting members 8. The clock proper is mounted in a cylindrical casing 10 which rests at its bottom on the plate 6 and at either side abuts the supports 8. A screw 12 extends through the plate 6 and engages threadedly in the wall of the casing 10 to hold the casing on the base.

Suitably mounted in the casing 10 is an electric coil 14 supplied with current through leads 16 extending through one side wall of the casing. This coil serves to energize the pole pieces 18, which in turn surround the rotor 20. This type of electric clock is well known and need not be described further.

The parts of the clock are mounted on two discs 22, 24 near the ends of the casing 10 and supported thereby. In front of these discs are provided the dials 26, 28, both facing outwardly. The pole members 18 are secured to the disc 22

by pins 30 near the bottom of the pole pieces. Screws 32 extend through the side walls of the casing 10 and threadedly engage in openings in the pins 30 so as to support and secure the pole pieces and thereby the disc 22 within the casing.

The rotor 20 is mounted on a shaft 34 which extends through and is journaled in the lower portions of the disc 22, and in a plate 182 mounted on the outer side of the disc 24. On the outer side 10 of the disc 22 this shaft carries a ratchet wheel 36 (Fig. 4). Pivoted on the outer side of the disc 22 and at one side of the ratchet 36 is a lever 38 swinging around a pin 40. A pawl 42 is pivoted at 44 to the end of the lever which is adjacent the ratchet 36. A spring 46 normally tends to turn this pawl in a counter-clockwise direction (Fig. 4), the movement of the pawl in this direction being limited by its engagement with a stop 48. The outer end or nose 50 of the pawl passes 20 when the lever swings about its pivot within the range of the teeth of the ratchet 36. A spring 52 secured to the lever and to a fixed portion of the disc 22 normally draws the lever upward. A stop 54 is provided to limit the upward movement 25 of the lever.

On the other end of the lever 38 is a pawl 56 pivoted at 58 to the lever. One end 60 of this pawl is normally spring pressed by a spring 62 to engage a stop 64 on the lever. It will be noted 30 that the pivot 58 is located well above the pivot 40 of the lever and that the stop 64 is arranged on the same side of the pivot 40 as the pawl 42. The pawl 56 also has an engaging flange 66 and a cam surface 68 on the opposite end from the projection 35 60.

A reciprocable member 70 has a slot 72 which engages pins 75, 76 and a screw 78 mounted in the disc 22. The screw 78 carries a plate 80 which overlies the member 70 and holds it in position. 40 The member 70 is thus constrained to move vertically past one end of the lever 38. A spring 82 secured to the member 70 and to a fixed part of the disc 22 normally draws the member 70 downward.

45 On the member 70 is a pin 84 which in the lower position of the reciprocable element is located below the engaging flange 66 of the lever 56. When the member 70 is drawn by its spring to its lowered position, it is lowered and extends 50 through registering openings 72, 74 in the plate 6 and base 2 to a considerable distance below the bottom of the base. The spring 82 is of such strength that the weight of the clock is sufficient to overcome its resistance and to raise the member 70. If now the clock is placed on a support, 55 the member 70 will engage the support and will be moved upwardly thereby. The pin 84 will engage the flange 66 and through the stop members 60, 64 will turn the lever 38 in a counter-clockwise direction (Fig. 4). During this movement, the lever is turned against the action of the spring and the nose 50 of the pawl 42, engaging the teeth of the rotor, is turned thereby against the action of the spring 46 and slides 60 over the teeth of the ratchet. After the member 70 has moved a certain distance, the pin 84 will pass the end of the pawl 56. When this occurs, 65 the lever 38 is released and under the action of the spring 52 turns back suddenly to its normal position. During this movement, the nose 50 of the pawl 42 engages the teeth of the ratchet and cannot be turned thereby because of the stop 48.

The sudden quick movement of the lever 38 is therefore imparted to the ratchet 36 and therefore to the rotor 20. In this way, a sudden force, 70 stored up in the spring 52, is imparted to the rotor to start the same.

When the clock is raised, the spring 82 moves the member 70 to extended position.

The pin 84, in moving downwardly, engages the cam surface 68 of the pawl 56 and pushes the pawl aside. As soon as the pin has passed the pawl, the spring 62 pushes the pawl 56 back to its engaging position. The device is thus reset so that an impulse will be given to the rotor when the clock is replaced 10 on its support.

The shaft 34 also carries a worm 86, and a shaft 88 mounted in supports 90, 92 on the disc 22 carries a worm wheel 94 in engagement with the worm 86. A shaft 96 extends through the centers 15 of the two discs and through the dials. On one end of this shaft and outside the disc 22 is secured a sleeve 98 carrying in front of the dial 26 the minute hand 100. On the other end of the shaft 96 and extending through the disc 24 is a 20 sleeve 102 freely rotatable on the shaft and journaled in an opening 104 in the disc 24. This sleeve carries on its outer end beyond the dial 28 a minute hand 106. Inside the disc 24 and secured to the sleeve 102 is a worm wheel 108. 25

Arranged on the shaft 88 are two worms 110, 112 the first of which engages with the worm wheel 114 secured on the shaft 96. The worm 112 engages a worm wheel 116 mounted on a shaft 118 transverse to the shafts 88 and 96. Secured on 30 shaft 118 is a worm 120 which engages the worm wheel 108 on the sleeve 102. It is obvious from the above that the sleeve 102 and shaft 96 will be driven in opposite directions and at the same speed provided the proportions of the gears are 35 properly chosen. In other words, the minute hands on the two dials will both move in clockwise directions to the eye of the observer.

A shaft 122 extends through the two discs 22, 24 somewhat above and to the side of the shaft 96. 40 On either end of this shaft are mounted sleeves 124, 126 each rotatable on the said shaft. These sleeves extend through openings in the discs 22, 24. The sleeves carry large gears 132, 134 and small gears 136, 138 rigidly mounted thereon. 45 The large gears engage with small gears 140, 142 rigidly mounted on the sleeves 98 and 102 respectively. The small gears 136, 138 engage with gears 144, 146 carried by sleeves 148, 150 which are rotatably mounted on the sleeves 98, 102 and 50 extend through the dials 26, 28 and carry on their outer ends the hour hands 152, 154. In this way, motion of the minute hands is transmitted to the hour hands at the proper reduced ratio.

The inner ends of the sleeves 124, 126 carry 55 bevelled gears 156, 158 both of which are engaged by a common bevelled gear 160 mounted on a shaft 162 transverse to the shaft 122.

A setting stem 164 is slidably arranged in a support 166 secured to the disc 22. This stem 60 extends through an opening 170 in the plate 6 and into an enlarged recess or depression 172 opening at the bottom of the base 2. The setting stem is normally spring pressed to its lowered position by a spring 174 which engages 65 at one end of the support 166 and at the other the knob 176 on the lower end of the stem. On the upper end of the setting stem is a bevelled gear 178 which when the stem is raised engages the gear 160 and thereby turns the 70 hands in opposite directions to set the clock.

Mounted on the outer faces of the discs 22, 24 are plates 180, 182, respectively which overlie the gears on the sleeves 124, 126 and form bearings for the ends of the shaft 122, thereby hold- 75

ing the gears in place on the ends of the shaft. The plate 182 also provides a bearing for one end of the rotor shaft 34.

The operation of the device will be clear from the foregoing. In the first place, it is evident that the movement of the rotor at a constant speed will drive the hands on the two dials in opposite directions at the same speed. The clock will therefore at all times show the same time on each dial. It is likewise obvious that the setting mechanism will turn both sets of hands simultaneously in opposite directions and to the same extent.

In regard to the starting mechanism, if the 15 clock stops because of a failure of current it is bound to lose some time. It is therefore totally unreliable until it is reset. In order to reset the hands, it is necessary to lift the whole clock in order to get access to the setting knob 20 176. After the hands are set, when the clock is replaced on the support the member 70 is pushed upwardly and thereby starts the rotor. It is obvious that the member 70 could be started by hand if it were so desired, and that the 25 sudden impulse would still be given to the rotor because of the sudden release of the lever 38.

While I have described herein one embodiment of my invention, I wish it to be understood that I do not intend to limit myself thereby except within the scope of the appended claims.

I claim:

1. In an electric clock, a non-self-starting motor including a rotor, and means operable by placing the clock on a support to impart movement to said rotor.
2. In an electric clock having a non-self-starting motor including a rotor mechanism to impart a starting movement to said rotor, reciprocal means to actuate said rotor starting mechanism, said reciprocal means extending through the bottom of the clock adapted to engage a support when the clock is placed thereon and to be moved by such engagement to impart movement to said rotor to start the clock.
3. In an electric clock having a non-self-starting motor including a rotor, a member vertically reciprocably mounted in said clock and normally extending through the bottom thereof so as to be moved when the clock is placed on a support, means operated by movement of said member for storing up energy, and means operated by further movement of said member to release said energy and to impart it suddenly to said rotor to start the same.
4. In an electric clock having a non-self-starting motor including a rotor, means for starting said rotor, said means comprising a ratchet wheel fixed to said rotor, a pivoted lever, a pawl pivoted on one end of said lever and normally spring

pressed away from said lever, said pawl engaging and turning said ratchet wheel when said lever swings in one direction and said pawl ratcheting over said ratchet wheel when the lever swings in the other direction, a spring normally urging said lever in said first direction, a second pawl pivoted on the other end of said lever, means to limit the rotary movement of said second pawl in one direction, a spring normally urging said second pawl to its limit of movement in said direction, said second pawl having a cam surface on the opposite side of its pivot from said movement limiting means, a member mounted to reciprocate past the second end of said lever, and a stop on said member adapted to engage said second pawl and to press it towards its movement limiting means to turn the lever against the action of its spring, said stop being then adapted to pass said pawl to release said lever whereby the energy of the spring is imparted to the rotor to turn the same, spring means for returning said reciprocal member to its initial position, said stop engaging during such return movement the cam surface of said second pawl to turn the pawl out of the path of the stop.

5. In an electric clock, a base having a depression in the bottom side thereof, a case mounted on said base, a non-self-starting motor in said case including a rotor, a dial, hands in front of said dial driven by said motor, means for setting said hands including a knob within said depression, whereby it is necessary to raise said base to set the hands, and means extending below said base and adapted to engage a support and be moved thereby when the base is replaced on the support 35 after a setting operation to impart starting movement to said rotor.

6. In an electric clock having a non-self-starting motor including a rotor, the combination with hands capable of being set manually only when 40 the clock is placed in an abnormal position, of means actuated by the return of the clock to normal position for imparting movement to said rotor.

7. In an electric clock having a non-self-starting motor including a rotor, manual means operable only when said clock is in an abnormal position for setting the hands, and means operable by the restoration of the clock to normal position for imparting movement to said rotor.

8. In an electric clock having a non-self-starting motor including a rotor, manual means, operable only when at least a portion of said clock is in an abnormal position for setting the hands, and means operable by the restoration of that 55 portion of the clock to normal position for imparting movement to said rotor.

IRVING FLORMAN.
